UNITED STATES PATENT OFFICE.

SIEGFRIED HIRSCHLER, OF WORMS, GERMANY.

GRAIN-TURNER.

SPECIFICATION forming part of Letters Patent No. 415,460, dated November 19, 1889.

Application filed August 6, 1889. Serial No. 319,892. (No model.)

To all whom it may concern.

Be it known that I, SIEGFRIED HIRSCHLER, a subject of the Emperor of Germany, residing at Worms, Germany, have invented new 5 and useful Improvements in Grain-Turners, of which the following is a specification.

The object of the invention is to provide a new and improved machine for conveniently and rapidly turning barley or other grain 10 while undergoing germination during the manufacture of malt.

The invention consists in certain parts and details and combinations of the same, as will be fully described hereinafter, and then pointed 15 out in the claims.

Reference is to be had to the accompanying drawings, forming a part of this specification, in which similar letters of reference indicate corresponding parts in all the figures.

20 Figure 1 is a plan view of the improvement. Fig. 2 is a side elevation of the same. Fig. 3 is an enlarged side elevation of a modified form of the turning-shovel wheel, and Fig. 4 is a sectional end elevation of the same on the line *x x* of Fig. 3.

The improved grain-turner A is placed in a room B over the floor or box C, containing the germinating barley or other grain to be occasionally turned to facilitate germination.

30 On the sides of the floor or box C are arranged the longitudinal rails D and D', on which are mounted to travel the rollers E E' and E² E³, respectively, supporting a carriage F, in which is mounted to turn the shovel-wheel G, 35 extending across the entire width of the box or floor C, and serving to turn the grain on the forward and on the backward motion. For this purpose the shovel-wheel G has double shovels—that is, shovels branching in 40 opposite directions, as is plainly shown in Figs. 2 and 4.

On one side of the carriage F is mounted to turn in suitable bearings a shaft H, carrying a grooved pulley I, over which passes an 45 endless rope J, also passing over the grooved rollers J' and J², mounted to turn on suitable studs held on one side of the carriage F. The endless rope J also passes over the grooved wheels J³ and J⁴, located opposite each other 50 at the end walls of the room B. The shaft J⁵ of the grooved wheel J⁴ carries a double clutch K, adapted to engage alternately the

clutches L and L', formed on the bevel gear-wheels L² and L³, respectively, on the shaft J⁵. Both bevel gear-wheels L² and L³ are in 55 mesh with a bevel-pinion L⁴, secured on a shaft L⁵, connected with suitable machinery imparting a rotary motion to the said shaft L⁵. The clutch K is thrown in contact with either of the clutches L or L' by the hand-lever K' engaging said clutch K. The double clutch K is automatically thrown out of contact with either of the said clutches by the carriage F whenever the latter arrives at one 60 end of the box or floor C. For this purpose the lever K' is connected by a rod K² with a lever K³, located opposite the lever K' at the other end of the box or floor C.

An arm F' is held on the carriage F, and is adapted to engage alternately the levers K' and K³, according to the direction in which the said carriage travels over the floor C. When the arm F' strikes either of the said levers K' or K³, the double clutch K is thrown out of contact with the clutch L or L', respectively. On the shaft H is held a pinion H', 65 meshing into an intermediate gear-wheel H², in mesh with the gear-wheel H³, secured on the axle E⁴, carrying the rollers E and E².

When the clutch K is in contact with either 70 of the clutches L or L', the respective gear-wheel L² or L³ turns said double clutch K, thereby turning the shaft J⁵ and imparting a rotary motion to the grooved wheel J⁴. The endless rope J, passing over the said grooved 75 wheel J⁴, imparts a rotary motion to the grooved pulley I, so that the shaft H is rotated, and the latter, by means of the gear-wheels H², H³, and H⁴, turns the axle E⁴, thereby turning the rollers E and E², whereby 80 the carriage F is forced to travel forward or backward over the box C on the rails D and D'. On the shaft H is also secured a gear-wheel N, which meshes into a gear-wheel N', 85 secured on one end of a hub G', mounted to turn in suitable bearings in the sides of the carriage F, and through which passes the axle E⁴, previously mentioned. The hub G' is part of the shovel-wheel G, and supports the radial arms G², which carry, at their upper 90 ends, the transversely-extending shovel-blades G³ and G⁴, arranged to extend in opposite directions, so as to turn the grain during the forward and backward motion of the 95 100

carriage F. When the latter moves forward and backward, as previously described, the shaft H turns and consequently imparts, by the gear-wheels N and N', a revolving motion 5 to the shovel-wheel G, whereby the respective shovel-blades G³ and G⁴ dip into the grain in the box C to lift the same and turn it over.

In order to agitate the germinating grain, forks O are arranged between the double shovel blades G³ and G⁴, as is plainly shown 10 in Fig. 2. Each of the forks comprises radial arms O', set into the hub G' and carrying at their outer ends transversely-extending boards O², in which are secured outwardly-projecting nails or spikes O³, as is plainly 15 shown in Figs. 1 and 2.

It is understood that the shovel-blades G³ and G⁴, when in their lowermost position, reach to within a short distance of the bottom 20 of the box C, as is plainly shown in Fig. 2, so that all the grain resting on the said box is turned over.

Instead of arranging the shovel-wheel G as 25 previously described, it may be made as shown in Figs. 3 and 4, in which the shovel-blades do not extend the entire length of the shovel, but are made shorter, and a series G⁵ of such shovel-blades is employed, set one behind the other across the box C, so that the shovels do 30 not pass simultaneously into the grain, but one after the other, thus relieving the machine of any undue strain.

In order to hold the carriage F on the rails D and D', one side of the carriage F is provided 35 with an arm P, carrying the rollers P' and P², traveling on the side of the rail D, as is plainly shown in Fig. 1.

The operation is as follows: The carriage F when at rest always stands at one end of the 40 floor or box C, the double clutch K then being out of mesh with both clutches L and L'. When the operator desires to turn the grain, he shifts the lever K', so that the double clutch K is shifted and engages either of the 45 clutches L or L', according to the direction in which the carriage F is to travel. The shaft J⁵ is thus rotated, whereby the rope J imparts a traveling motion to the said carriage F by the means previously described. The carriage F moves slowly forward, and the shovel-wheel G is rotated at the same time in the direction opposite to the forward movement of the carriage F. The respective shovel-blades G³ or G⁴ pass into the grain, lift the same up, 55 and throw it down again, thereby turning it over. As soon as the carriage F reaches the respective end of the floor or box C, the arm F' comes in contact with either lever K' or K³, thus forcing the lever K' to move the 60 double clutch K out of contact with the respective clutch L or L'. The carriage F thus comes to a standstill, and at the same time the rotary motion of the shovel-wheel G ceases. The apparatus is then at rest usually for several 65 hours, and when the operator again de-

sires to start the machine on its return movement he has to shift the lever K', so that the double clutch K engages the clutch L or L', respectively. The above-described operation is then repeated.

It is understood that as the shovel-blades G³ and G⁴ are curved the grain falls out of the respective blade at about a quarter-revolution of the wheel G after the grain is packed up.

Having thus described my invention, what I claim as new, and desire to secure by Letters Patent, is—

1. The combination, with the parallel longitudinal guide-rails, of a grain-turning wheel 80 having a hollow hub G', journaled in the sides of the carriage and provided at one projecting end with a pinion N', the axle E⁴, passing through said hub and provided at its ends with rollers E E², traveling on said rails, and 85 with a gear-wheel H³ between roller E² and pinion N', the short shaft H, provided with a gear N, meshing into pinion N', and with a pinion H', a pinion H², meshing into gear H³ and pinion H', means for rotating the shaft 90 H and reciprocating the carriage, and rollers E' E³ on opposite sides of the carriage traveling on the rails, substantially as set forth.

2. The combination, with the parallel longitudinal rails D D' and the pulleys J³ J⁴ at 95 the ends thereof, of a reciprocating carriage provided at its opposite sides with rollers E' E³, traveling on said rails, a short shaft H at the center of one side and provided with gear-wheel N, pinion H', and pulley I, the grain-turning wheel having a hollow hub journaled at its ends in the sides of the frame and provided with a pinion N', meshing into the gear-wheel N, the axle E⁴, extending through the said hub and provided beyond the ends of the 105 hub with rollers E E², traveling on the said rails, and with a gear-wheel H³, the gear H², meshing with pinion H', gear H³, the pulleys J' J² above and at opposite sides of the pulley I, the endless driving-strand J, passing at 110 its upper side under pulley I and over pulleys J' J², and a reversing mechanism, substantially as set forth:

3. In a grain-turner, the wheel G, provided with arms G², having oppositely-projecting 115 double shovels G³ G⁴ at their outer ends, and the forks O, arranged between the pairs of shovels and each comprising radial arms O', having transversely-extending bars O² at their outer ends provided with central and outer 120 oppositely-projecting nails or spikes O³, substantially as set forth.

In testimony whereof I have signed my name to this specification in the presence of two subscribing witnesses.

SIEGFRIED HIRSCHLER.
